US00D755706S

(12) **United States Design Patent**
Roach et al.

(10) **Patent No.:** US D755,706 S
(45) **Date of Patent:** ** May 10, 2016

(54) **STORAGE CONTAINER FOR USE WITH A VEHICLE**

(71) Applicants: **Robert Roach**, Holt, MI (US); **Craig Wieland**, Mason, MI (US)

(72) Inventors: **Robert Roach**, Holt, MI (US); **Craig Wieland**, Mason, MI (US)

(**) Term: **14 Years**

(21) Appl. No.: **29/510,387**

(22) Filed: **Nov. 26, 2014**

Related U.S. Application Data

(63) Continuation of application No. 29/449,629, filed on Mar. 15, 2013, now Pat. No. Des. 722,009.

(57) **CLAIM**

The ornamental design for a storage container for use with a vehicle, as shown and described.

DESCRIPTION

FIG. 1 is an isometric view of a storage container for use with a vehicle in an erected configuration.

FIG. 2 is a side view of the storage container for use with a vehicle of FIG. 1 in the erected configuration.

FIG. 3 is another side view of the storage container for use with a vehicle of FIG. 1 in the erected configuration.

FIG. 4 is another side view of the storage container for use with a vehicle of FIG. 1 in the erected configuration.

FIG. 5 is another side view of the storage container for use with a vehicle of FIG. 1 in the erected configuration.

FIG. 6 is a top plan view of the storage container for use with a vehicle of FIG. 1 in the erected configuration.

FIG. 7 is a bottom plan view of the storage container for use with a vehicle of FIG. 1 in the erected configuration; and, FIG. 8 is another isometric view of the storage container for use with a vehicle of FIG. 1 in the erected configuration.

The features shown in broken lines are for illustrative purposes only and do not form part of the claimed design.

1 Claim, 7 Drawing Sheets
